WOOD POLE PROTECTIVE MEANS

Filed June 17, 1929

FIG. 1.

FIG. 2.

Inventor
GEORGE W. HAMILTON

By *Frank H. Pecklin* Attorney

UNITED STATES PATENT OFFICE

GEORGE WELLINGTON HAMILTON, OF EVANSTON, ILLINOIS

WOOD-POLE-PROTECTIVE MEANS

Application filed June 17, 1929. Serial No. 371,680.

The invention relates to power line installation and has special reference to means for protecting the wooden poles used for supporting transmission lines against damage in the event of a flash-over which may occur as the result of lightning.

It is well known that wood pole construction is used largely for the benefit derived from the insulation effect provided by the wood. However, when use is made of the wood as insulation, there are a number of conditions to be considered as, for example, the wood may be wet or it may be dry at the time of the lightning flash-over. Furthermore, if the hardware, suspension devices, braces, etc. on the pole are not grounded or partially grounded through a gap, the wood is almost certain to be burned or otherwise damaged by the lightning discharge.

It is with the above facts in view that I have devised the present invention which has for its principal object the provision of a protective gap or plurality of gaps on the pole, at least certain of the metallic elements forming the gap or gaps being grounded, the purpose being to permit the lightning discharge to jump the gap and pass to the ground.

An important object of the invention is to provide a protective device for this purpose which will not interfere with or detract from the insulating value of the wood but which will at the same time act to safeguard the same against burning or other destruction.

A more specific object of the invention is to provide a protective device embodying arcing horns mounted upon the cross bar of a wooden supporting pole structure, certain of the arcing horns being associated and electrically connected with the metallic elements which support the insulators which in turn carry the transmission lines or conductors, and the others being suitably grounded in same convenient manner.

An additional object of the invention is to provide an arrangement of this character which will be simple and inexpensive to make and install, positive in action, efficient in service, and a general improvement in the art.

To the attainment of the foregoing and

other objects and advantages, the invention preferably consists in the details of construction and the arrangement and combination of parts to be hereinafter more fully described and claimed, and illustrated in the accompanying drawing in which:

Figure 1 is a side elevation of a wooden supporting structure of a transmission line showing an embodiment of the invention, and

Figure 2 is a top plan view.

Referring more particularly to the drawing, the numeral 1 designates upright wooden supporting poles which carry a wooden cross arm 2 from which are suspended strings or chains of suspension insulators 3 carrying clamps 4 which support the conductors 5. While the invention can be carried out in conjunction with insulators of the pin type, it lends itself very readily to that type of installation where suspension insulators are employed, for which reason this type is illustrated. The strings of insulators 3 are here shown as hanging from bolt-like members 6. It is customary to provide metal braces 7 for the cross arm 2, these braces being appropriately mounted upon the poles 1 as shown at 8 and being secured to the cross arm as by bolt members 9 passing therethrough. Usually, the poles are guyed as shown at 10 though this is an immaterial detail in this case.

In carrying out the invention I provide a plurality of pairs of arcing horns 11, three sets being shown in the present instance as there are three suspended conductors, though it should be understood that there may be fewer or more depending upon circumstances. One arcing horn is mounted at each of the bolt-like members 6 which support the strings of insulators, and another in each set is located at one of the bolt members 9 which secure the arms 7 in place. The exact mechanical construction of these arcing horns is naturally a matter which may be varied within wide limits as it is easily possible to make their bases 12 somewhat in the nature of nuts for the bolts 6 and 9. This arrangement would be very convenient and inexpensive and is indicated in the drawing. The horns are represented as of curved shape and those in each pair extend toward each other

with their terminals preferably equipped with or formed as balls 13 spaced apart to provide a gap 14, the exact length of which is probably immaterial, at least within certain limits. The most advantageous gap distance may be ascertained by experiment. By this arrangement it is clear that certain of the horns are in electrical connection with the metallic suspension elements for the insulator strings while the others are in electrical connection with the metallic braces 7. These braces are intended to be grounded and this is readily done by means of conductors 15 connected therewith and brought down either inside or outside the poles and extending into the earth. For the sake of illustration, these ground wires or conductors are shown as wrapped about the bases of the poles as indicated at 16 though it is readily apparent that any other equivalent arrangement may be resorted to.

Assuming that the installation has been effected as shown and described, or in an equivalent manner, it is apparent that in the event of a lightning discharge, the charge will jump across one or more of the gaps 14 and be conducted to the ground, thereby protecting the wood against burning, shattering or rupture. The protective system will operate equally well under wet or dry wood conditions and is extremely efficient as it provides an easy path for the lightning flash-over. Furthermore the arrangement is such as not to detract in any way from the insulating value of the wooden installation itself. It is believed that from the foregoing the construction, operation and advantages will be readily understood by one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. In a supporting structure for transmission lines including a wooden cross arm, a bolt passing through said cross arm for supporting a string of insulators therefrom, and an arcing horn adapted to seat on said bolt and a cooperating arcing horn on said structure, said last named horn being connected to ground.

2. In a transmission line system a supporting structure including a wooden cross arm, a string of insulators mounted thereon by means of a metallic bolt, and an arcing horn detachably connected to said bolt, another

arcng horn connected to said arm by means of the arm supporting member, said last named horn being connected to ground and being spaced from said first named horn.

3. In a transmission line system a supporting structure having a wooden cross arm, a line conductor and means for supporting the same including a metallic bolt carried by said cross arm, an arcing horn detachably connected to said bolt and a second arcing horn supported on said structure and connected to ground and in spaced relation to said first named horn, the adjacent portions of said horns being spaced apart so that the insulating value of the air gap separating the same is less than that of said supporting structure. 70

4. In a supporting structure for transmission lines including a wooden cross arm, a string of insulators mounted thereon by means of a metallic connector and arcing horn adapted to be detachably connected to one end of said metallic connector, a brace for said cross arm connected to ground and another arcing horn electrically connected to said brace and spaced from said first named 80 horn. 85

5. In a transmission line arrangement, a wooden supporting structure, insulators mounted thereon by means of metallic elements, and a plurality of arcing horns on said structure, certain of said horns being grounded and others being in physical and electrical contact with said elements, the horns being spaced apart to form limited air gaps. 90

In testimony whereof I affix my signature.
GEORGE WELLINGTON HAMILTON.
